(57) **CLAIM**

The design of a large narrow all terrain utility cart, as shown and described.

DESCRIPTION

FIG. 1 is a left three dimensional view of the large narrow all terrain utility cart according to our design;

FIG. 2 is a bottom right three dimensional view thereof;

FIG. 3 is a top right three dimensional view thereof;

FIG. 4 is a bottom left three dimensional view thereof;

FIG. 5 is a rear elevation view thereof;

FIG. 6 is a front elevation view thereof;

FIG. 7 is a left elevation view thereof;

FIG. 8 is a right elevation view thereof;

FIG. 9 is a top plan view thereof; and,

FIG. 10 is a bottom plan view thereof.

The broken lines showing of the wheels depict environment that form no part of the claimed design.
